JOHN B. BORGADT, OF EAST CLEVELAND, OHIO

ELECTRIC TRANSFORMER

Substitute for application Serial No. 95,649, filed March 18, 1926. This application filed January 8, 1931.
Serial No. 507,513.

The present invention relates in general to electric transformers, and more particularly to transformers of that type which are adapted for use in connection with electric welding machines, being designed to give a current of high amperage and low voltage. This application is a substitute for my application, Serial No. 95,649, filed March 18, 1926 and allowed January 26, 1929.

10 While the electric transformer of this application may be used in connection with any conventional form of electric welding machine, it is especially adapted for use in connection with the tube welding machine for 15 which Patent No. 1,580,401 was granted to me on April 13, 1926.

Among the objects of the invention are to provide a secondary winding which is divided into a plurality of spaced sections, 20 the spacing between the sections permitting air cooling of the coil and being adapted to be varied to obtain a predetermined impedance.

A further object of the invention is to 25 provide a novel means for supporting the secondary winding independently of the primary winding.

While one particular embodiment of the invention is shown and described in detail 30 in this application, it will be understood that many modifications and changes can be made in the details of construction without departing from the spirit of the invention.

For a full understanding of the invention, 35 reference is to be had to the following description and accompanying drawings in which:

Fig. 1 is a side elevation of an electric transformer which is constructed in accordance with the invention; Fig. 2 is an end view thereof; Fig. 3 is a horizontal sectional view on the line 3—3 of Fig. 1; Fig. 4 is a top plan view of one of the lower bracket members; Fig. 5 is a side elevation thereof; Fig. 6 is a top plan view of one of the upper bracket members; Fig. 7 is a side elevation thereof, one end of the bracket being broken away; Fig. 8 is an enlarged detail perspective view of one of the combined supporting and insulating members for the outer edges of

the secondary winding; and Fig. 9 is a similar view of one of the insulating and supporting members which are interposed between the two sections of the secondary winding.

Corresponding and like parts are referred to in the following description and indicated on all of the views of the drawings by like reference character.

Referring to the drawings, the reference character A designates a laminated iron core which forms a continuous magnetic circuit, being formed with the intermediate cross bar 1 and the end cross bars 2. The intermediate cross bar 1 supports the primary windings and, as shown on the drawings, there are four sections 3 of primary windings which are applied to the cross bar 1 and held firmly in place by the frame.

Applied to the top of the core A at opposite ends of the primary coils are the upper brackets 4. In a similar manner lower brackets 5 are applied to the bottom of the core at opposite ends of the primary winding. The upper and lower brackets are formed at end and intermediate portions thereof with corresponding eyes 6 which project laterally and receive tie bolts 7. These bolts engage the edges of the laminated core A to hold the said core in place and are tightened to hold the laminæ together. The base portion of each of the upper and lower brackets 4 and 5 is also formed with an intermediate foot member 8 and end feet 9. These feet project laterally from the brackets and rest upon the laminated core A, the intermediate feet 8 entering the end sections 3 of the primary winding.

The secondary winding is formed in two units B, B, each of which comprises a single turn built up of thin flexible copper strips or laminæ to the required current carrying capacity necessary for welding purposes. Each unit B of the secondary winding comprises a plurality of strips or sections which may be variably spaced to obtain a larger or a smaller internal reactance as may be desired for the particular work to be done. As shown on the drawings, each unit B comprises an inner strip 10, an intermediate strip 11, and an outer strip 12, said strips being spaced and gradually decreasing in thickness from the inner

strip to the outer strip. The spacing between the strips provides for air cooling of the winding, and in designing the transformer these spaces can be made larger or smaller to obtain a larger or a small internal reactance. The strips 10, 11 and 12 have a laminated formation, being built up to the required current carrying capacity from laminæ which are usually .010 or .015 inch in thickness. Ordinarily no portion of the secondary is more than $\frac{5}{8}$ ths of an inch in thickness, it being a known fact that alternating current of commercial frequencies does not penetrate beneath a surface stratum, so that any metal in a conductor above this thickness, whether laminated or solid, is useless.

The secondary winding which comprises the two units B, B is supported independently of the primary and is rigidly held in position to resist the thrusts to which it is subjected by the electromagnetic action of the transformer. Insulating blocks 13, one of which is shown by Figure 9, are interposed at suitable intervals between the units B, B, while the outer edges of the units are engaged by insulating blocks 14, one of which is shown by Fig. 8. The insulating blocks 13 and 14 are formed in their faces with grooves 15 which receive edge portions of the strips 10, 11 and 12 of the respective units B of the secondary winding. The insulating blocks 14 are shown as formed in their outer faces with openings 16 which are adapted to receive positioning pins 17 projecting from arms 4^a of the upper bracket 4 and arms 5^a of the lower bracket 5. Corresponding arms of the upper and lower brackets are connected by cross bolts 18 which pass through openings in the ends of the arms and also pass through openings 19 in the intermediate insulating blocks 13. By tightening these bolts the upper brackets 4 and lower brackets 5 are drawn toward each other so that the sections or strips of the units B of the secondary winding are firmly seated in the grooves 15 of the insulating blocks 13 and 14. The intermediate insulating blocks 13 are held in position by engagement with the cross bolts 18, while the outermost insulating blocks 14 are held firmly in proper position by engagement with the positioning pins 17. The proper spacing between the sections 10, 11 and 12 of the secondary winding is thus rigidly maintained and by substituting different insulating blocks the spacing between the sections or concentric strips of the secondary winding can be varied. This arrangement provides the designer with greater flexibility and enables him to accurately predetermine the operating characteristics of the transformer. The lower brackets 5 are also shown as formed with depending feet 5^b which are of assistance in properly supporting the transformer in position when it is in use.

⁵ The ends of the split or divided secondary

winding each terminate in two arms 20 between which a lead 21 is inserted. Each of the leads is clamped to the arms 20 at the respective end of the secondary winding by means of the bolts 22 and plates 23, whereby the large contact area necessary for carrying a heavy welding current is obtained. The intermediate strip or division 11 of each unit of the secondary winding has the ends thereof divided and a portion thereof connected to one side of the arms thereof, while the other portion thereof is connected to the other side arm 20.

The invention provides a construction whereby the secondary winding is rigidly supported independently of the primary winding and is in spaced relation thereto so that air can circulate between the same for preventing overheating. The secondary winding is also divided into divisions or strips which are rigidly supported to resist the electromagnetic thrusts, and which may be variably spaced to obtain the desired impedance. This is an improvement over the ordinary transformer of this type in which the secondary is loosely built up of laminæ without spacing or supports, and with this transformer the heavy currents necessary for electric welding can be obtained.

What I claim is:

1. An electric transformer including a secondary winding which comprises a wide conductor strip, and insulator supports fitted against opposite edges thereof and formed with notches to receive the edges of the strip. 95
2. An electric transformer including a secondary winding comprising a plurality of wide conductor strips arranged in a side by side relation, brackets on opposite sides of the secondary winding, tie bolts connecting the brackets, and insulator supports engaging the edges of the wide conductor strips, certain of the insulator supports being carried by the brackets and others being mounted on the tie bolts. 105
3. An electric transformer including a secondary winding which is divided longitudinally into a plurality of independent sections, and readily exchangeable means for rigidly supporting the sections in various predetermined spaced relations to obtain a desired impedance. 115
4. An electric transformer including a laminated secondary which is divided longitudinally into a plurality of sections, insulators engaging the sections, and means cooperating with the insulators to clamp the sections rigidly in a spaced relation. 120
5. A transformer including a secondary winding, brackets on opposite sides thereof, insulators carried by the brackets and engaging the secondary winding, and cross bolts connecting the brackets to maintain the insulators in operative engagement with the secondary winding. 125

6. An electric transformer including a magnetic core, a primary winding thereon, brackets applied to the magnetic core, tie bolts connecting the brackets to clamp them in position on the core, a secondary winding, and means for supporting the secondary winding in a spaced relation to the primary winding by means of other bolts connecting the brackets. 5
7. An electric transformer including a magnetic core, a primary winding thereon, brackets applied to opposite sides of the core, tie bolts connecting the brackets to clamp them against the core, a secondary winding, insulators engaging the secondary winding, and other bolts connecting the brackets and serving to clamp the insulators in a rigid engagement with the secondary winding to support the same in a spaced relation to the primary winding. 10
8. An electric transformer including a magnetic core, a primary winding thereon, opposed brackets applied to the edges of the magnetic core on opposite sides thereof, tie bolts connecting the brackets to clamp them against the core, a secondary winding, cross bolts connecting the brackets and arranged at substantially right angles to the tie bolts, and means cooperating with the cross bolts to support the secondary winding in a spaced relation to the primary winding. 15
9. An electric transformer including a magnetic core, a primary winding thereon, corresponding brackets applied to opposite sides of the magnetic core and provided with lateral feet which fit against the magnetic core and extend within the primary winding, tie bolts connecting the brackets to clamp them against the magnetic core, a secondary winding, other bolts connecting the brackets, and means cooperating with the other bolts to provide a rigid support for the secondary winding. 20
10. An electric transformer including a magnetic core, a primary winding thereon, brackets applied to opposite sides of the magnetic core, tie bolts connecting the brackets to clamp them against the magnetic core, a secondary winding comprising a plurality of wide conductor strips arranged in a side by side relation, intermediate supports interposed between the conductor strips and engaging the same, end supports interposed between the brackets and the conductor strips, and bolts connecting the brackets for holding the supports in operative engagement with the conductor strips. 25
11. An electric transformer including a magnetic core, a primary winding thereon, brackets applied to opposite sides of the magnetic core, tie bolts connecting the brackets to clamp them against the magnetic core, a secondary winding including a plurality of wide conductor strips, intermediate insulator supports interposed between the conductor strips and engaging the same, end insulator blocks supported by the brackets and engaging the edges of the conductor strips, and cross bolts connecting the brackets and engaging the intermediate insulator supports, said cross bolts serving to hold the insulator supports in a firm engagement with the conductor strips of the secondary winding. 30
12. An electric transformer including a secondary winding, which comprises a wide conductor strip, insulator supports engaging opposite edges of the conductor strip, and means for holding the insulator supports firmly in operative position. 70
13. An electric transformer including a secondary winding which comprises a plurality of wide conductor strips arranged in a side by side relation, intermediate supports interposed between the conductor strips, and supports engaging the outer edges of the conductor strips, side brackets, and cross bolts connecting the side brackets and holding the insulator supports in operative engagement with the conductor strips of the secondary winding. 80
14. An electric transformer including a secondary winding which comprises a plurality of wide conductor strips arranged in a side by side relation, each of the conductor strips being divided longitudinally into a plurality of spaced sections, and means for rigidly supporting the strips with the longitudinal divisions thereof in a spaced relation to each other. 85
15. An electric transformer including a secondary winding which comprises a wide conductor strip, said strip being divided longitudinally into a plurality of sections, insulator supports engaging the edges of the strip and formed with notches to receive the divisions thereof, and means for clamping the insulator supports against the conductor strip. 90
16. An electric transformer including a secondary winding which comprises a wide conductor strip, said strip being divided longitudinally into a plurality of spaced sections arranged one within another and with their width towards the primary, and unitary means for rigidly supporting the strip with the longitudinal divisions thereof in spaced relation to each other. 100
